United States Patent Office

Des. 223,788
Patented June 6, 1972

223,788

POCKETBOOK

Juliana M. Corridon, 7805 Takoma Ave.,
Takoma Park, Md. 20012

Filed Nov. 15, 1968, Ser. No. 14,477

Term of patent 14 years

Int. Cl. D3—02

U.S. Cl. D87—3

FIG. 1

FIG. 3

FIG. 4

FIG. 2

FIG. 6

FIG. 1 is a front perspective view of pocketbook showing my new design;

FIG. 2 is a rear elevation thereof on an enlarged scale;

FIG. 3 is a side edge view thereof;

FIG. 4 is a top plan view thereof;

FIG. 5 is a rear perspective view of a modified form of the pocketbook of FIG. 1 wherein the outline is in the form of a heart; and

FIG. 6 is a front perspective view of a modified form of the pocketbook of FIG. 1 wherein the outline is in the form of a square.

I claim:

The ornamental design for a pocketbook, as shown and described.
